ENAMELED METAL WALL CONSTRUCTION

William Hogenson, Hinsdale, Ill., assignor to Chicago Vitreous Enamel Product Co., Chicago, Ill., a corporation of Illinois

Application August 9, 1935, Serial No. 35,436

15 Claims. (Cl. 20—15)

This invention relates to enameled metal wall construction of a type particularly suited for use in the erection of new, or the remodeling of old buildings, homes, filling stations, and the like.

In my copending application entitled "Enameled metal wall construction", Serial No. 742,029, filed August 30, 1934, there is disclosed a construction wherein the enameled metal plates are prefabricated on insulation board backing so as to provide individual panels of metal veneered board that can be readily assembled in the construction of internal or external walls. Since there is no interlocking of the panels with each other, any panel can be quickly and easily removed from the face side without disturbing any of the adjacent panels.

The metal panels, which usually become warped at the high temperatures employed for burning on the enamel, are cemented under high pressure to rigid insulating boards, both for the purpose of pressing the enameled metal to straighten it out and also to eliminate the tendency of the metal to buckle under climatic conditions. Furthermore, the heavy insulating boards not only prevent sweating of the metal but also act as sound deadener and heat insulation. In wall construction, these panels are supported in spaced relation and the resulting joints are all caulked, so that no metal touches metal and the edges of the panel are protected by a waterproof caulking compound. All of the edges of the enameled metal panels are, at the same time, protected against rusting by the caulking compound.

The present invention contemplates the use of metal veneer panels of the type described, but of an improved construction, in the erection of external or internal walls of porcelain enameled metal. The invention also contemplates the use of improved retaining strips and cover trim of a uniform, standardized form and appearance, as well as the use of standardized base and ceiling molding formed from rolled or stamped metal.

It is therefore an object of this invention to provide a metal veneer wall construction that can be simply and inexpensively erected owing to the fact that the elements of the wall are largely prefabricated and are of uniform, standard design so as to be interchangeable.

It is a further important object of this invention to provide an enameled metal wall construction in which prefabricated enameled metal panels of standard size and shape may be used in the con-

struction of the side walls and similar but slightly differently constructed metal panels may be used in the ceiling.

Other and further important objects of this invention will be apparent from the disclosures in the specification and the accompanying drawings.

This invention (in a preferred form) is illustrated in the drawings and hereinafter more fully described.

On the drawings:

Figure 1 is an elevational view, partly broken away and in section, of a side wall construction embodying the principles of my invention.

Figure 2 is a fragmentary enlarged sectional view taken substantially on the line II—II of Fig. 1.

Figure 3 is a broken, fragmentary enlarged sectional view taken substantially on the line III—III of Fig. 1.

Figure 4 is a fragmentary enlarged detail view of the wall base construction.

Figure 5 is a fragmentary enlarged broken away elevation view of a wall joint.

Figure 6 is an enlarged, broken sectional view of the ceiling and ceiling corner construction.

Figure 7 is a fragmentary sectional view taken substantially on the line VII—VII of Fig. 6.

As shown on the drawings:

The reference numeral 10 (Fig. 1) indicates generally a wall of porcelain enameled metal embodying the principles of my invention. The wall 10, as shown, is an internal wall but the same general construction applies to external walls as well. The wall 10 is joined by another side wall 11 of similar construction and is provided with a ceiling 12. The wall 11 is separated by a space 13 from a wall 14 of similar construction but oppositely spaced, the walls 11 and 14 thus forming a complete wall partition, such as would be used between two adjoining rooms.

The wall 10 comprises a supporting framework of wood formed of vertically extending studding 15 and horizontally extending stringers 16 and a base furring strip 18. The studding and stringers are put up in the usual way at properly spaced intervals and joined together to make a rigid supporting framework for enameled metal panels 17. The stringers 16 may be formed integrally, or as best indicated in Fig. 2, may be provided with separate strips 18 secured thereto and extending along one of the broad faces of each stringer. The strips 18 are formed with a longitudinally extending central groove 19, which may suit-

ably be key-shaped to retain the plastic caulking compound 20 with which it is filled.

Each of the panels 17 comprises a backing of rigid insulation board 21 and a metal veneer 22 secured thereto by waterproof adhesive 23. The panels 17 are prefabricated by cementing the metal veneer 22 to the insulation board 21 under high pressure so as to obtain a smooth surface that will not buckle under climatic conditions. 10 The metal veneer 22 is preferably provided with a porcelain enamel surface, which may be of any desired color and which may be either highly glazed, or have a matt or rough surface.

Each metal panel 17 may have flanges 24 and 25 extending along opposite edges, which may be either the short or long edges, as desired, but not both. These flanges 24 and 25 lie beyond the end edges 26 and 27, respectively, of the insulation board 21 by a distance sufficient to permit the flanges 24 and 25 to extend into the grooves 19 and be embedded therein in the caulking 20. The caulking also extends between all of the joint surfaces as at 28 and 29 between the panels 17 and the strips 18 and studding 15. The 20 dimensions are such that the flanges 24 and 25 are spaced apart and also from the body of the strips 18, whereby the metal of the panels is free to expand and contract.

The other edges of the metal veneer on the 30 panels 17 are not flanged but extend somewhat beyond the corresponding edges of the insulation board, as indicated at 30 (Fig. 3). These extended edges 30, when the panels are assembled, are in spaced relation overlying the horizontal stringers 16. Said stringers 16 have strips 31 extending along their broad working faces, the strips 31 being either integrally formed with the stringer or separately formed and attached thereto. Retainer strips 32 are positioned along 40 and in overlapping relation to the extended edges 30 and are secured in place by means of screws or nails 33 that are threaded into the strips 31. The space inside of the retainer strip 32, as well as the entire joint, is then filled with a waterproof 45 caulking compound that remains plastic over an extended period. A composition containing tung oil and asbestos makes a satisfactory caulking compound.

The retainer strip 32 may be formed of stamped 50 or rolled sheet metal with reversely rounded lateral edges 34 that are adapted to be brought into snug engagement with the extended metal edges 30 by threading home the screws 33.

An outside cover trim 35 is so constructed as to 55 be readily snapped in place over the rounded lateral edges 34 of the retainer strips 32. Said cover trim 35 may suitably be made of stainless steel or other non-corroding metal or metal alloy of pleasing surface characteristics. Each cover trim 60 35 is provided with reversely bent lateral edges 36 which, because of the inherent resiliency of the metal itself, can be snapped over the rounded edges of the retainer strips 32 and held in place thereon without other fastening means.

65 In making the ceiling 12, panels 37 are used, which are similar in general construction to the panels 17 but slightly different therefrom in that the metal veneer 38 is provided all around with side flanges 39 that extend over the end edges of 70 the insulation board backing 40. The corner edges of each panel 37 are cut away, as at 41, to provide a space 42 between the corners of adjacent panels for the insertion of fastening means, such as the screw 43. Said screw 43 carries at 75 its headed end a disk or washer 44 which overlies

substantial corner portions of the assembled panels. The disk or washer 44 may take any desired ornamental form or design, and may even be made of glass, since the weight of the panels 37 is comparatively little.

As best shown in Fig. 6, the ceiling panels 37 are sustained solely by means of the fastening means 43 from the stringers 45, except for the panels next adjacent the side walls 11. The tops of said side walls 11 comprise horizontally extending wooden strips 46 which are either formed integrally with or secured to stringers 47 forming a part of the supporting frame. Each strip 46 is provided with a ceiling molding strip 48 formed from stamped or rolled sheet metal and having a generally angular cross section. One of the webs 49 of said ceiling molding 48 extends along and is secured to the upper face of the strip 46, as by means of screws 50. The outer web 51 of said ceiling molding 48 is spaced from and parallel to the inner plane surface of the strip 46 and is provided with a reversely bent flange 52 also parallel to said face. Although the flange 52 is normally resiliently held against the face of the strip 46, prior to assembly of the side walls 11, during assembly the extended marginal portion 53 of the metal panel 54 is inserted therebetween. The space between the web 51 of the ceiling molding 48 and the strip 46 is filled with caulking 55, as are also other portions of the joint. There is thus formed a water tight joint.

The ceiling panels 37 adjacent the side walls 11 rest directly upon the leg 49 of the ceiling molding 48, as indicated at 57 (Fig. 6). By virtue of the fact that no fastening means are used but merely a surface to surface contact, free relative movement between the contacting parts due to contraction or expansion is permitted.

The side walls 11 are supported upon base furring strips 58 (Figs. 3 and 4) which have strips 59 integrally formed therewith or secured thereto. To each of said strips 59 is secured a base molding 60 of generally similar design to the ceiling molding 48. Said base molding 60 has its horizontal web 61 secured to the strip 59 by screws or other attaching means 62. An upright web 63 extends substantially parallel to and spaced from the front plane face of the strip 59 and is provided with a reversely bent flange 64 that is resiliently urged toward said plane face. The space between the web 63 and the strip 59 is filled with a caulking compound 65. The whole assembly of base furring strip and molding is preferably prefabricated in proper lengths.

When the metal veneer panels 17 are mounted in place, the lower extended edges 66 of the metal veneer are inserted into the space formed between the flange 64 and the face of the strip 59, the flange 64 thereafter, because of the resiliency of the metal, pressing firmly against the metal veneer. This type of molding permits greater tolerances in the dimensioning of the panels.

It will be understood that both the base and ceiling molding may be prefabricated with their corresponding furring strips or the like. The vertical studding 15 and the stringers 16 are likewise prefabricated and cut to size for the particular job for which they are to be furnished. In the erecting of the wall structures, therefore, it is a simple matter to first put up the supporting frame-work of studding, stringers, furring strips, and the like, and then build up the fin-

ished wall by inserting the individual wall panels 17 in place in the framed openings. After all joints have been properly caulked the retainer strips and cover trim are positioned in place. In the finished wall structure, the edges of the metal veneer are in spaced non-interlocking relation and protected against rusting by being embedded in the caulking compound. Each panel is readily and quickly removable, upon removal of the cover trim and retainer strip, without disturbing the next adjacent panel.

The ceiling panels 37 are secured in place by means of fastening devices 43 and 44 with clearances between adjacent metal veneers to allow 15 for expansion and contraction.

I am aware that many changes may be made and numerous details of construction may be varied through a wide range without departing from the principles of this invention, and I, therefore, do not purpose limiting the patent 20 granted hereon otherwise than necessitated by the prior art.

I claim as my invention:

1. A wall structure comprising structural supporting members having longitudinally extending slots containing caulking, insulation panels abutting said strips and metal plates adhesively secured to said panels and having integral flanges extending into and embedded in said 25 caulking.

2. A wall structure comprising members extending at right angles to each other, strips on said members in one direction having longitudinal slots filled with caulking, strips on said 35 members in the other direction having plane faces, panels of insulation board positioned between said strips to lie against said members, metal plates secured to said panels and having flanges along opposite edges extending into said 40 caulking and embedded therein, the other edges of said panels being spaced apart along said plane strip faces, and trim overlying said spaced apart edges to conceal the same.

3. A wall structure comprising wooden studding having raised strips extending at right angles to each other to define rectangularly shaped openings, the strips in one direction having keying grooves filled with caulking, panels of insulation board set in said openings, metal plates secured to said panels and having edge flanges 50 extending into said grooves and embedded in said caulking.

4. A wall structure comprising wooden studding having raised strips extending at right angles to each other to define rectangularly shaped openings, the strips in one direction having keying grooves filled with caulking, panels of insulation board set in said openings, metal plates secured to said panels and having edge flanges 60 extending into said grooves and embedded in said caulking, other edges of said metal plates being spaced apart along other studding strips, and trim overlying and concealing said other edges and secured to said other studding strips.

5. A wall structure comprising wooden studding having raised strips extending at right angles to each other to define rectangularly shaped openings, the strips in one direction having keying grooves filled with caulking, panels of insulation board set in said openings, metal plates secured to said panels and having edge flanges extending into said grooves and embedded in said 65 caulking, there being caulking in the joints between said panels and said studding and strips.

6. A wall structure comprising wooden studding

having raised strips extending at right angles to each other to define rectangularly shaped openings, the strips in one direction having keying grooves filled with caulking, panels of insulation board set in said openings, metal plates secured to said panels and having edge flanges extending into said grooves and embedded in said 5 caulking, other edges of said metal plates being spaced apart along other studding strips, trim overlying and concealing said other edges and secured to said other studding strips, said trim consisting of a metal band fastened to said strips and having rounded edges and a second metal band having edge flanges resiliently engaging said rounded edges.

7. A wall joint structure comprising a wooden member, a panel of insulating board abutting said member, a metal plate secured to said panel and having a marginal edge overlying a face of said member, and a metal trim secured to another face of said member and having a reversely bent flanged portion parallel to said first face and resiliently engaging said marginal edge.

8. A preformed wall joint element comprising a strip of wood of rectangular cross section and a stamped metal molding of angular cross section having one web secured to a face of said wooden strip and a second web substantially parallel to but spaced from the corresponding face of said strip, said second web having a reversely bent flange urged against said corresponding face by the resiliency of the metal itself.

9. A preformed wall joint element comprising a strip of wood of rectangular cross section and a stamped metal molding of angular cross section having one web secured to a face of said wooden strip and a second web substantially parallel to but spaced from the corresponding face of said strip, said second web having a reversely bent flange urged against said corresponding face by the resiliency of the metal itself, the space between said second web, flange and corresponding face of said strip being filled with caulking.

10. A wall structure comprising a wooden supporting frame having members extending at right angles to each other, members of the frame in one direction having grooves filled with caulking, flanged metal veneer panels mounted on said frame with the flanges extending into and embedded in said caulking and retainer strips secured to the members extending in the other direction and overlying adjacent edges of said panels.

11. The method of erecting a wall structure using metal veneered insulation board panels, which comprises erecting studding and stringers to provide a supporting frame having openings of the proper dimensions to receive said panels while leaving expansion joints between the edges of adjacent metal veneering, caulking the joints so formed, securing metal strips over some of said expansion joints and applying cover trim over said metal strips.

12. A wall construction comprising structural members defining panel receiving framed openings, metal veneer panels having insulation board backing adapted to fit into said openings with the metal veneer of adjacent panels overlapping said intervening structural elements but out of metal contact with each other and caulking between all surfaces of the joint thus formed and protecting the edges of the metal veneer against rusting.

13. A wall construction comprising structural members defining panel receiving framed open-

- ings; metal veneer panels having insulation board backing adapted to fit into said openings with the metal veneer of adjacent panels overlapping said intervening structural elements but out of metal contact with each other, caulking between all surfaces of the joint thus formed and protecting the edges of the metal veneer against rusting and cover trim over the edges of said metal veneer extending in one direction only.
- 10 14. A wall construction comprising structural members defining panel receiving framed openings, metal veneer panels mounted in said openings with the metal veneer overlapping the structural elements but in spaced relation to the metal
- 15 veneer of adjacent panels and retaining strips overlapping but not interlocking adjacent edges of panels and removable to permit the removal of any one panel without disturbing the next adjacent panel.

16. A wall structure comprising structural supporting members including spaced vertically extending strips, a base strip and spaced horizontally extending strips providing framed openings, the vertically extending strips being grooved, panels of metal veneered insulation board set into said framed openings with the metal veneer overlying the margins of said strips and having flanges extending into said grooves, caulking material in said grooves filling the same and covering said flanges, metal base trim secured to said base strip and having a reversely bent flange overlying and resiliently engaging the lower edges of the lower row of panels and caulking material within and sealing the joint thus formed. 15

WILLIAM HOGENSON.
